Feigin & Associates, LLC(57) **CLAIM**

The ornamental design for a bendable grabbing device, as shown and described.

DESCRIPTION

FIG. 1 is a top and side perspective view of a bendable grabbing device.

FIG. 2 is a bottom and side perspective view of the device.

FIG. 3 is a side elevation view of the device, the opposite side being a mirror image.

FIG. 4 is a back elevation view of the device.

FIG. 5 is a front elevation view of the device; and,

FIG. 6 is a side elevation view of the device, turned 90 degrees from that of FIG. 3, the opposite side being a mirror image.
